UNITED STATES PATENT OFFICE.

RALPH S. WYETH, OF NEWARK, OHIO.

CONVERTIBLE BODY.

1,289,997.

Specification of Letters Patent.

Patented Dec. 31, 1918.

Application filed May 29, 1918. Serial No. 237,291.

To all whom it may concern:

Be it known that I, RALPH S. WYETH, a citizen of the United States, residing at Newark, in the county of Licking and State 5 of Ohio, have invented certain new and useful Improvements in Convertible Bodies, of which the following is a specification.

This invention relates to a convertible body for motor driven vehicle, and has for 10 its principal object to provide a body structure which may be conveniently and quickly adjusted to assume an open or extended position, whereby the body may be utilized for commercial or delivery purposes, or to assume a folded or collapsed position to render 15 the vehicle adaptable for ordinary touring or pleasure purposes, whereby when the body is folded to occupy this latter position, no objectionable parts thereof are exposed 20 to the eye and the symmetry and graceful appearance of the body preserved.

In carrying out the invention use is made 25 of a body comprising a stationary section and a swinging or movable section, said sections being so constructed that when the movable section is moved to assume its open or extended position, the body is lengthened to its maximum extent and the storage capacity thereof is correspondingly increased, whereby various commodities may 30 be placed in the body for transportation purposes, and, conversely, when the said swinging section is oscillated to assume its folded or inactive position the same will 35 considerably shorten the general proportions of the body by telescoping as it were within the stationary section, so that the body as a whole when in this latter position will present an incased appearance with accompanying 40 pleasing outlines, and closely resembling the so called "turtle back" body commonly found upon automobiles of the roadster variety.

Another object of the invention resides in 45 providing the swinging section with a plurality of guides at each end thereof, which guides are adapted to receive a removable end member, whereby the latter is capable of being employed to incase the rear extremity of the body in both its folded and extended positions.

Further objects are to produce a convertible body of the character stated and of such construction as to be capable of being 50 expensively and easily mounted in connection with a motor vehicle, of substantial and

efficient construction, and capable of being conveniently manipulated to assume its dual positions.

With these and other objects in view, as 60 will appear as the description proceeds, the invention accordingly consists in the novel features of construction, combination of elements, and arrangement of parts hereinafter fully described and having the scope thereof 65 defined by the appended claims.

In the drawing, wherein has been shown the preferred embodiment of the invention:

Figure 1 is a perspective view of the convertible vehicle body comprising the present 70 invention and illustrating the latter in its open or extended position and adapted for delivery or commercial purposes,

Fig. 2 is a vertical sectional view taken through the vehicle body when the same 75 occupies the position shown in Fig. 1,

Fig. 3 is a similar sectional view disclosing the body in its folded or inactive position, and

Fig. 4 is a transverse sectional view taken 80 along the line 4—4 of Fig. 3.

Similar characters of reference denote like parts throughout the several views of the drawing.

Referring more particularly to the details 85 of the invention, the vehicle body A comprising the present invention is preferably mounted upon the rear of an underframe 1 and also to the rear of the vehicle seat 2. While, it will be understood, that the body 90 A is preferably adapted for vehicles of the roadster class and has been thus illustrated, it is not strictly essential to adhere to this form of vehicle, as the body A with slight and unimportant modifications may be 95 adapted with equal facility to other forms or types of vehicles, but inasmuch as the roadster type of vehicle admirably discloses the features of application of the invention, the following description will be limited to 100 that particular form.

The body A consists of a stationary section 3 and a foldable or movable section 4, each of the sections comprising base and side walls 5 and 6 respectively. The stationary section 3 is adapted to be secured in any suitable manner upon the frame 1 and the forward end of this latter section flushly engages, as shown, with the rear wall of the vehicle seat 2. A ledge 7 is secured to the upper edges of the side 6 and extends 105 transversely of the section 3 and immedi-

ately adjacent to the seat 2; the function of this ledge will presently appear. The side walls of the modified section 4 are secured to corresponding walls of the stationary section 3 by means of bolts 8, which pass centrally and transversely through said side walls, in the manner shown in Fig. 4. These bolts are preferably surrounded by means of sleeves 9, which permit of the free oscillation of the movable section with respect to the stationary section. Nuts or their equivalent 10 are carried upon the outer ends of the bolts 8, and serve to retain the latter in their operative positions within the sides 6.

15 The movable section 4 has its sides equipped with guides 11 which latter are located at each end of said section, and are adapted to receive a removable end member 12, which member is adapted to be shifted 20 from one set of guides to the other in accordance with the position occupied by the movable section 4. Spring locking devices 13 are carried by the stationary section, and are adapted to engage with the base of the 25 movable section when the latter is oscillated to assume its folded position, in order to prevent the latter from rattling or vibrating.

In operation, when it is desired to place the body A in condition for the reception of 30 commodities to be delivered, or in other words to convert the body to positions of utility, the movable section is oscillated about the bolts 8, until its base wall 5 registers or comes into contact with the rear 35 edge of the base wall forming a part of the stationary section. This limits further rearward or oscillating movement of the movable section, and as will be observed upon reference to Fig. 1 extends or enlarges the 40 receiving area of the body A and opens the latter to receive articles for transportation. When the movable section occupies this extended position, the end member 12 is moved to occupy the rear set of guides 11, for the 45 obvious purpose of preventing articles positioned within the body from accidentally falling out or becoming otherwise disposed. However, if the vehicle upon which the body is mounted is simply desired to be employed 50 for ordinary pleasure or touring purposes, the movable section is oscillated to fold or telescope within the stationary section 3, in the manner clearly shown in Fig. 3. This results in providing a body of standard appear- 55 ance and will not disclose the fact that the vehicle can be used for commercial purposes, this being accomplished by preserving the graceful appearance of vehicle bodies employed merely for passenger services.

60 The base wall of the movable section extends beyond the margins confined by its side

walls 6, so that when said movable section is moved to assume its folded position, these extended marginal portions will engage with the upper edges of the side walls 6 65 formed upon the stationary section, this results in limiting the folding movement of the movable section. Furthermore, it will be noted that when in its folded position, the base wall of the movable section will 70 register with the ledge 7, thus presenting an inclosed body devoid of objectionable spaces or gaps. Prior to the moving of the section 4 to assume its folded position, the end member 12 is moved to occupy the 75 guides 11 located contiguous to the bolts 8, so that when the section 4 finally occupies its folded position, said end member will be located at the extreme rear end of the body A, as shown in Fig. 3.

80 From the foregoing description taken in connection with the accompanying drawing, it will be perceived that there is provided a vehicle body of considerable utility and desirability, as it enables a single vehicle to be employed for purposes of transporting commodities or for ordinary pleasure use, hence overcoming the objection to placing a delivery body upon an ordinary passenger car.

90 I claim:

1. The combination with a vehicle body, of a receptacle located to the rear of said body, said latter consisting of a stationary section and a foldable section, means for 95 pivotally securing the latter section to the stationary section, whereby the foldable section may be oscillated to assume a collapsed position within said stationary section or may be swung to assume an open and ex- 100 tended position, and a back member separably carried by the foldable section and adapted to be inserted in either one of a pair of guides located at each end of said latter section.

105 2. The combination with a vehicle body, of a rearwardly situated strong receptacle mounted upon said body, said receptacle comprising stationary and foldable sections, each of said sections including base and side walls, means for pivotally connecting the side walls of said sections, whereby when the foldable section is moved to assume an open position said base walls will meet to limit the swinging movement of the foldable 110 section, and a removable rear member carried by said foldable section and adapted to be situated in guides formed at each end of said latter section.

115 In testimony whereof I affix my signature. 120

RALPH S. WYETH.
